E. T. TURNERY

TELEPHONE HEADSET

Filed April 26, 1922

Inventor
Eugene T. Turney

By his Attorney
Philip S. McLean

UNITED STATES PATENT OFFICE.

EUGENE T. TURNER, OF HOLMES, NEW YORK, ASSIGNOR TO EUGENE T. TURNER LABORATORIES, INC., OF NEWARK, NEW JERSEY, A CORPORATION OF NEW JERSEY.

TELEPHONE HEADSET.

Application filed April 26, 1922. Serial No. 556,573.

To all whom it may concern:

Be it known that I, EUGENE T. TURNER, a citizen of the United States, and a resident of Holmes, Dutchess County, and 5 State of New York, have invented certain new and useful Improvements in Telephone Headsets, of which the following is a specification.

The present invention relates to head sets 10 such as are used in radio telephony.

The objects of the invention are to provide a particularly sensitive telephone receiver of this character which will fit well to the head, holding the phones in close engagement with the ears, but without uncomfortable or excessive pressure at any point, and which, furthermore, will be light in weight, attractive in appearance and quickly and easily adjustable to fit the wearer.

20 These and other objects are attained in the embodiment of the invention disclosed in the accompanying drawing which, however, is to be considered as illustrative of the form the invention may take, it being obvious that certain changes and modifications may be made in the structure without departing from the true spirit and scope 25 of the invention.

Figure 1 in the drawing referred to is 30 a side elevation.

Figure 2 is a front view of the head set in the position of normal use.

Figure 3 is a sectional plan on line 3—3 of Figure 1.

35 The head band structure consists in the present disclosure of a pair of relatively light spring wires 5 which are shown covered with suitable webbing 6, these wires being arched to lightly clasp the top of the head, and having convergent end portions secured to the end plates 7. In the illustration these plates are made of sheet metal and the anchorage of the wire ends thereto is accomplished by bending lugs 8 40 at the side edges of the plates over the ends of the wires.

45 At their upper and lower ends the plates 7 are shown as having outwardly bent lugs 9 perforated at 10 to provide aligned bearings for posts attached to the individual phones.

The posts or connectors are of novel construction in that they consist in each instance of a flat spring strip doubled upon 55 itself to form a spring post 11 slidingly

engaging in the bearings 10, the lower ends of the strips being arched apart to form a fork fitting about the case of the phone and carrying pivot lugs 12 engaging in sockets therefor provided in the phone case. 60

The doubled portions of the spring strips are separated sufficiently to provide the spring tension for frictionally holding the posts in vertically adjusted relation in their sockets and the corners provided at the 65 edges of these flat strips operate to hold the posts in their angularly turned relations; consequently, while the phones can be very readily adjusted both vertically and angularly, they will automatically hold 70 themselves in the positions in which they have been set.

What I claim is:

1. In a telephone head set, a head band carrying spaced lugs perforated to provide aligned bearings, a telephone receiver and a post connected therewith slidably and rotatably engaged in said bearings, said post comprising longitudinally separated strips spaced under spring tension to each 75 yieldingly grip the bearings at longitudinally separated points. 80

2. In a telephone head set, a head band carrying spaced lugs perforated to provide aligned bearings, a telephone receiver, and a post connected therewith slidably and rotatably engaged in said bearings, comprising longitudinally separated strips spaced under spring tension to each yieldingly grip the bearings at longitudinally 85 separated points, said strips having angular corner edges presented to the bearings and the bearing lugs having angular edges adjacent the corner edges of the strips. 90

3. In combination, a telephone receiver, a support therefor having a bearing and a supporting post for the receiver, slidably and rotatably engaged in said bearing and comprising a single strip of flat spring material doubled upon itself to provide spaced substantially parallel longitudinally extending spring tensioned members frictionally held in the bearing by their tendency to straighten the strip and spaced at their lower ends to form a fork embracing the receiver, said fork ends having pivot studs associated therewith for pivotally supporting the receiver. 95

4. In a telephone head set, a head band having a sheet metal bracket at one end of 100 105 110

the same provided with outwardly bent substantially parallel lugs separated to provide spaced bearings, a telephone receiver and a supporting post for said receiver comprising a single strip of spring metal doubled upon itself to form a stem made up of spaced substantially parallel spring tensioned members frictionally engaged with the outstanding bearing lugs, the lower ends

of said folded strip being spread apart at ¹⁰ the base of the parallel sided stem to form fork arms, said arms having pivot studs engaged with the receiver case.

In witness whereof, I have hereunto set my hand this 6th day of March, 1922.

EUGENE T. TURNERY.

Reexecuted April 10 1922.

EUGENE T. TURNERY.
